UNITED STATES PATENT OFFICE

BURTON H. COOK, OF NEW YORK, N. Y.

SUSPENDERS.

No. 820,624.

Specification of Letters Patent.

Patented May 15, 1906.

Application filed April 7, 1905. Serial No. 254,330.

To all whom it may concern:

Be it known that I, BURTON H. COOK, a citizen of the United States, residing in the borough of Brooklyn, county of Kings, city 5 and State of New York, have invented certain new and useful Improvements in Suspenders, of which the following is a specification.

This invention relates to suspenders, and aims to provide certain improvements therein.

10 In the usual form of suspender as now constructed the necessary elasticity is provided for by forming the webbing with rubber strands, the two straps of elastic webbing being united at their rear ends by a reinforce 15 of leather, which also serves as a means of attachment for the usual bifurcated tab for buttoning to the back of the trousers, similar tabs being adjustably connected to the front ends of the straps for supporting the front 20 portion of the trousers. Suspenders constructed in this manner are open to several objections. The rubber contained in the straps or webbing speedily loses its elasticity, the leather reinforce being exposed to the 25 perspiration of the body rapidly deteriorates, and the entire suspender has a very short period of usefulness. My invention provides a suspender which is open to none of these 30 objections, which contains no rubber or leather, which is not liable to breakage, which permits entire freedom of movement without binding upon the wearer or placing an undue strain upon the suspender, and which is simple in construction and inexpensive to 35 manufacture.

To these ends in the preferred form of my invention I provide a suspender the straps of which are formed of one continuous piece of inelastic fabric, the middle of which is connected to the rear tab and the ends of which are connected to the front tabs by spring connections, which are adapted to provide the necessary elasticity for the suspender. Such 45 connections are preferably formed of a plurality of helical springs of elliptical cross-section, which are designed to have a definite degree of expansion or contraction, being limited thereto by a stop device which is preferably flexible and which is adapted to assume 50 the strain when the springs have reached their prescribed limits of stress.

My invention provides several other features of improvement, which will be herein-after more particularly described.

55 Referring to the drawings, which illustrate several modifications of my invention, Figure

1 is a view of one of the front ends of a suspender, showing the spring connection in its normal condition. Fig. 2 is a view of the rear end, illustrating the springs stretched to 60 their limit. Fig. 3 is a view illustrating the flexibility of my improved connection. Fig. 4 is a plan of several parts of the suspender separated. Fig. 5 shows an edge view and a cross-section of the preferred form of spring. 65 Fig. 6 is a view of a modified form of the spring connection. Figs. 7 and 8 are views illustrating modified forms of spring. Fig. 9 is a view of a detail.

Referring to the drawings, let A indicate 70 the suspender-straps, a in Fig. 2 designating the left-hand strap and a' the right-hand strap, one of such straps a being shown in Fig. 1. In the preferred form of my invention the straps a a' are constructed of a single 75 piece of inelastic webbing or other suitable fabric folded at its middle, as shown in Fig. 9, the fold being passed through a loop b and turned back upon the body portion and being attached to the latter by rivets or other suitable devices c. The formation of a fold at this point is rendered desirable by the fact that the ordinary commercial webbings are woven with a right and a wrong side, and if the webbing were merely passed through the 80 loop b the two sides would not correspond. With a double-faced webbing the latter construction may be adopted. In either case the use of leather at this point is rendered superfluous, and a greater degree of strength 85 and durability is secured with a gain in simplicity of construction.

According to my invention each of the tabs B B' is connected to the loop b or other equivalent device by a yielding connection 95 which I will designate as a whole by the letter C. In its preferred form this consists of two or more helical springs d, which are preferably flattened to give them an elliptical cross-section, one of such springs being shown 100 in edge view in Fig. 5. By so forming the springs I am enabled to obtain great strength and durability without the formation of a bunch or hump which would press into the body of the wearer, and on this account 105 be so objectionable as to render their use impracticable. The springs are preferably connected at their upper ends to the loop b by means of a plate e, which is bent around the loop and is provided with perforated lugs or eyes e' on its lower side, through which the ends of the springs are passed. The plate e,

previous to being bent around the loop *b*, is shown in Fig. 4. A similar connection is made to the tab-hook *f* at front and the tab-loop *g* at rear.

5 I prefer to provide a stop for limiting the stress upon the springs, whereby when the latter have been extended or contracted to the desired extent the strain will be removed therefrom and taken up by the stop, so that 10 the springs will not be injured by any excessive strain. Such a stop may be constructed in a number of different ways, but that which I prefer is shown in Figs. 1, 2, and 15 3, and consists of a flexible member, such as 20 a chain *h*, which is connected to suitable eyes *e*², formed in the plates *e* and normally hangs loosely, as shown in Fig. 1. When the springs have been stretched, however, to the extent shown in Fig. 2, for instance, the 25 chain *h* becomes taut, and entirely relieves the springs from any further stress. It is preferable that the chain *h* or other flexible stop should be arranged between the springs, as shown in Figs. 1 and 2; but it may be arranged as shown in Fig. 6, wherein the chain is outside of the series of springs, in this construction two chains being preferably used. Any other suitable means for connecting the 30 springs and chain with the webbing may be employed; but such means should preferably permit a free movement of the springs and chain around their points of connection, as shown in Fig. 3. By this construction I provide a spring connection which permits 35 any reasonable movement of the wearer without placing any undue strain upon any part of the suspender. Fig. 3 illustrates the capability of the connection for wide movements without in any way twisting or disturbing 40 the parts, so that the suspender imposes no restraint upon the movements of the wearer and exerts no undue pressure upon his body. The connection permits such movements 45 equally in any direction whether the springs be stretched or not.

In the suspender shown a very strong and durable construction of bifurcated tab is provided, which I will describe with reference to Fig. 4. The tab is constructed of a flexible band of braid or other fabric *i*, which is formed in a single continuous piece looped at *j*, Fig. 1, and provided with clasps or clamps *k* to limit the size of the buttonholes thus formed. The two ends of the braid are joined 50 together by a suitable clamp *l*, Fig. 4, which is provided with projections *m m* (shown in dotted lines in this figure) and with serrated edges *n n*, which are bent over upon the ends of the braid, forcing the serrations and projections into the fabric and clamping the ends 55 tightly together, as shown in Fig. 1. The middle part *o* of the double tab thus formed is then placed within a serrated clamping-plate *p*, Fig. 4, the portions *q* of which are 60 then bent over upon the braid, securely clamping 65 the latter in place.

As thus constructed a much stronger union between the clamping-plate and braid is formed than would be the case were the two ends of the braid clamped within the plate or if the two tabs were made 70 separately and their ends clamped by the plate, as heretofore. The clamping-plate is formed with a projecting portion *r*, which is bent around the ring or loop *g* or *g'*, depending upon whether the tab is to be used 75 at the rear or in front of the suspender. A snap-hook *s* is usually provided at each of the front ends, which engages the ring or loop *g'*.

In Fig. 7 I have illustrated a modified construction of spring adapted for use with my 80 invention. In this form the spring is placed under compression by any strain upon the suspender-straps, two rods *t t'*, bearing against opposite ends of the spring, being provided for this purpose. Each of the rods, as shown, 85 extends through the spring and is provided at one end with an arm *t²* or *t³*, engaging the ends of the spring and through which the other rod slides. Each rod is formed with a hook at its opposite end, by which it may be 90 attached to the eye *e*. Another form of spring which may be used for this purpose is illustrated in Fig. 8. As shown, this comprises two bow-springs *d² d³*, which are adapted to be compressed by rods *u u'*. Each of 95 the rods is provided with a head *u²*, bearing against one spring, and is adapted to slide through a hole in the opposite spring. The rods in this case are also provided with suitable hooks for engaging the eyes *e*. 100

Any suitable number of springs may be employed in any of the constructions shown, depending upon the degree of elasticity required. In Figs. 1 to 3, for instance, I have shown two springs, and in Fig. 6 three; but a 105 few or greater number may be employed, if desired.

The suspender provided by my invention has many advantages over those now in use. I am enabled to dispose entirely with rubber 110 in any form, and no seams or stitching are required. I also avoid the use of leather or any other material which is affected by the perspiration of the body, all of the metal parts being preferably of nickel, brass, or 115 other metal which is rust-proof and non-corrodible. The various parts are made in the strongest possible manner for a given weight of material and are of simple and inexpensive construction. Preferably all three of the 120 spring connections are of the same construction, so that they may be used interchangeably, thus avoiding unnecessary multiplication of parts.

Although I have described in detail the 125 preferred embodiment of my invention, I do not wish to be limited thereto, as many changes may be made therein without departing from the invention.

I claim as my invention the following de- 130

fined novel features substantially as hereinbefore specified:

1. In a suspender, the combination with a suspender strap and tab, of a yielding connection interposed between said parts, said connection comprising a spring having its ends pivotally connected to said parts so as to swing in all directions without distorting itself or said strap and tab.
2. In a suspender; the combination with a suspender strap and tab, of a yielding connection interposed between said parts, said connection comprising a flattened helical spring having its ends pivotally connected to said parts so as to swing in all directions without distorting itself or said strap and tab.
3. In a suspender, the combination with a suspender strap and tab, of a yielding connection interposed between said parts, said connection comprising a plurality of helical springs having their ends pivoted to said parts, so as to swing in all directions without distortion.
4. In a suspender, the combination with a suspender strap and tab, of a yielding connection interposed between said parts, said connection comprising a plurality of flattened helical springs arranged with their flat sides in the plane of said strap, and having their ends pivoted to said parts so as to swing in all directions without distortion.
5. In a suspender, the combination with a

suspender strap and tab, of a yielding connection interposed between said parts, said connection comprising a spring having its ends 35 pivotally connected to said parts so as to swing in all directions without distorting itself or said strap and tab, and a flexible stop for limiting the stress upon said spring.

6. In a suspender, the combination with a suspender strap and tab, of a yielding connection interposed between said parts, said connection comprising a plurality of flattened helical springs arranged with their flat sides 45 in the plane of said strap, and having their ends pivoted to said parts, so as to swing in all directions without distortion, and a flexible stop for limiting the stress upon said springs.

7. In a suspender, a strap, a tab, plates attached to said strap and tab respectively, perforated lugs formed on said plates, a plurality of flattened helical springs having their opposite ends pivoted in said lugs, and a flexible stop adapted to limit the stress upon said 55 springs, said stop being connected at its opposite ends to said plates.

In witness whereof I have hereunto signed my name in the presence of two subscribing witnesses.

BURTON H. COOK.
